US0D1075361S

(12) **United States Design Patent** (10) **Patent No.:** **US D1,075,361 S**
(45) **Date of Patent:** **** May 20, 2025**

(54) **PILLOW**

(71) Applicant: **SLEEPSLEEK LLC**, Cheyenne, WY (US)

(72) Inventors: **Mehmet Kaya**, Antalya (TR); **Yusuf Kaya**, Garland, TX (US)

(73) Assignee: **SLEEPSLEEK LLC**, Cheyenne, WY (US)

(**) Term: **15 Years**

(21) Appl. No.: **29/957,263**

(22) Filed: **Aug. 13, 2024**

(51) **LOC (15) Cl.** **06-09**

(52) **U.S. Cl.**

USPC **D6/601**

(58) **Field of Classification Search**

USPC D6/596, 597, 601, 604; D24/190, 191
